UNITED STATES PATENT OFFICE.

THEODORE CORNUELLE, OF CINCINNATI, OHIO.

MOLD FOR THE MANUFACTURE OF CONCRETE BLOCKS.

1,260,147.

Specification of Letters Patent. Patented Mar. 19, 1918.

Application filed September 20, 1917. Serial No. 192,249.

To all whom it may concern:

Be it known that I, THEODORE CORNUELLE, a citizen of the United States, residing at Cincinnati, in the county of Hamilton and State of Ohio, have invented certain new and useful Improvements in Molds for the Manufacture of Concrete Blocks, of which the following is a specification.

This invention relates to molds, or forms 10 for the manufacture of concrete blocks.

The object of my invention is to provide a simple and efficient mold which can be constructed of metal, easily assembled and knocked down, and the parts conveniently 15 dipped in oil before the concrete is poured thereinto.

Another object of my invention is to provide a mold which will produce a block the face of which will appear as a cement brick 20 face.

Another object of my invention is to provide a mold in which boulders may be conveniently placed before filling with concrete, or, portions of bricks and the like may 25 be inserted methodically, so that the concrete may be poured in around them, thereby providing a block which when completed has the appearance of boulder brick or stone masonry.

Still another object of my invention is to provide means whereby a series of molds or cells may be built up by stringing the parts thereof along a beam or beams, which might be readily called arbors, so that when the 35 molds are assembled they may be securely clamped on the said arbors, forming a single unit comprising a series of cells for blocks.

In the accompanying sheets of drawings which show a preferred construction of my 40 invention,

Figure 1 is a perspective of a mold constructed in accordance with my invention and resting on a suitable floor.

Fig. 2 is a perspective of a partly assembled 45 portion of a mold showing more clearly the construction of the cores employed and the manner of stringing the molds on a square arbor.

Fig. 3 is a perspective of a side plate of 50 the mold.

Fig. 4 is an elevation of the front of one of the cores employed.

Fig. 5 is a perspective of one of the cores.

Fig. 6 is a top plan of the bottom of the 55 mold showing the recesses provided therein and boulders in place.

Fig. 7 is a side elevation of same after the block has been molded.

Figs. 8 and 9 are similar views showing the bottom of the mold arranged for the 60 reception of portions of brick, stone or the like.

Fig. 10 is a perspective of the block when completed to represent brick masonry.

Referring more particularly to the drawings: 1 represents an end plate which may, if desired, be a permanent one. This plate is provided with square apertures through which the square arbors 2 are adapted to pass.

In describing the following parts they 70 will be described in the order in which they are used in assembling a complete mold.

It will be understood that two core holes 3 are usually provided in each concrete block so that two arbors 2 are provided. Cores 4 75 are first strung upon the arbors 2 as in Fig. 2 and consist of a substantially square or rectangular frame open at the ends. The metal frames are preferably constructed of a material having a certain amount of spring 80 thereto so that they may be contracted slightly when it is desired to knock down the mold after the block is completed.

Fastened along the central part of each side of the core and projecting inwardly, 1 85 provide a brace block 6, the inner exposed face of which engages the arbor 2 when the core is strung thereon. The sides of the core, before being strung upon the arbor 2 assume a somewhat collapsed form as shown 90 in Fig. 5 and are held in this position by springs 7 extending diagonally across the corners of the core at each end thereof and on the inside. Thus the brace blocks are held in a position which allows a small passageway between them at the center of the core for the arbors 2 to pass.

The arbors are provided with tapering ends 19 so that the cores may be forced thereon against the pressure of the springs 100 7. When forced thereon the sides of the core are forced to their straight position as shown in Fig. 2, thereby forming flat surfaces on the outside of the core for molding the core hole 3.

The cores 4 are passed along the arbors 2 until they engage the end plate 1 and then the dividing plate 8, Fig. 3, is strung along the arbors 2. The plate 8 is provided with square apertures 9 of the same shape as the 110 arbors 2, and are also provided with flanges 10 at the ends, the said flanges extending at

right angles thereto forming braces and stops for the end plates which will be described. Similar flanges 11 are provided at the bottom of the dividing plates 8 to support the floor of the mold or cell.

End plates 14 are provided and are inserted at the ends of each cell resting against the inside of the flanges 10 of the dividing plates 8. Projections 15 on the end plates 10 at one end of the cell, and channels 16 at the other end are provided to form the tongue 15^a and groove 16^a respectively on the completed blocks for convenience in building. Any desired number of these 15 tongues and grooves may be provided on each block by providing for same on the mold end plates 14.

The cores 4 and dividing plates 8 are alternately strung upon the arbors 2 until a sufficient number of cells have been provided 20 to produce say about ten blocks.

The bottom plates 12, Figs. 7 and 9, are then inserted and rest on the flanges 11 of the dividing plates 8 and are equipped with 25 a series of partitions or upwardly extending projections 13 so arranged as to allow boulders, bricks and the like to be inserted in the pockets or recesses formed thereby; or when nothing is inserted the concrete of 30 a fine consistency is poured into them thereby forming a block the face of which will appear as being made up of cement bricks.

After the parts of the mold are all assembled the molds are drawn tightly together 35 by means of driving wedges 17 into elongated openings in the arbors a short distance, the wedges bearing against the outside of the end plates and one end of the said slots. The wedges are preferably provided 40 with a shoulder 18 which marks the limit of its path and forms a gage for tightening up the molds.

The floor 20 shown may be the floor of a car if desired, and is cut away at 21 to allow 45 lifting means to be inserted under the blocks when they are ready to be removed from the car or floor 20.

It will be seen that owing to the simplicity of the construction of the different 50 parts of the device that the parts can all be conveniently dipped in a solution or in oil very easily, before being assembled, which has been found to be a very necessary step in the process when using metal molds.

When it is desired to knock down the mold 55 after the blocks are hard, the wedges 17 are knocked out of the arbors and the arbors drawn out. As soon as the arbors are drawn out the cores 4 collapse slightly, making it 60 an easy matter to draw them out in their turn.

It will be noted that when bricks of any color or type are used in the face of the block, that only one half of the brick need 65 be used, thereby greatly reducing the cost of

the bricks over a brick veneer job such as are well known. It will also be understood that stone masonry can be imitated to advantage by arranging accordingly the strips 12 on the bottom plates of the molds. Furthermore, the projections 12 may be constructed so as to leave a shoulder around the surfaces imitating stone so that the same may be chiseled or pitched off to imitate the finer chiseled or pitched quality of stone masonry. 75

Having thus described my invention what I claim as new and desire to secure by Letters Patent is:

1. A mold of the character described comprising an arbor, side plates on said arbor 80 forming the sides of said mold, a core on said arbor between said side plates, bottom and end plates, means on said side plates for holding said bottom and end plates in proper position, and means for drawing said 85 side plates together whereby the parts of the mold are clamped together.

2. A mold of the character described comprising a series of divisional plates forming the sides of the cells of the mold, arbors 90 passing through said plates, cores on said arbors and disposed between said plates, end plates, bottom plates, and means whereby all of said plates and cores are clamped tightly together on said arbor, substantially as described. 95

3. A mold of the character described comprising an arbor, side plates on said arbor forming the sides of said mold, a core on 100 said arbor, said core comprising a metal rectangular frame open at the ends, blocks mounted on the inside walls of said frame, said blocks extending inwardly to engage the arbor, springs fastened to the sides of said frame tending to draw the sides of the 105 frame inwardly, bottom and end plates, means for holding said bottom and end plates in proper position, and means for drawing said side plates together, whereby the parts of the mold are clamped together. 110

4. A mold of the character described comprising an arbor, side plates on said arbor forming the sides of said mold, a core on 115 said arbor, said core disposed between said side plates, a bottom plate, said bottom plate provided with upwardly extending projections forming pockets for bricks, boulders, stones and the like, end plates, means on said side plates for holding said bottom and end plates in proper position, and means for drawing said side plates together where 120 by the parts of the mold are clamped together, substantially as set forth.

5. A mold of the character described comprising an arbor, side or partition plates 125 each provided with an aperture through which said arbor is adapted to pass, flanges on the ends and bottom of said side plates, a core on said arbor between said side plates, bottom and end plates adapted to engage 130

said flanges, and means for drawing said side plates together whereby the parts of the mold are clamped together, substantially as set forth.

5 6. A mold of the character described comprising a pair of arbors tapered at one end thereof, side plates having apertures to accommodate said arbors, contracting cores adapted to be strung upon said arbors and
10 disposed between said side plates, end and

bottom plates, one of said end plates being provided with a vertical projection and the other with a corresponding channel to form a tongue and groove at opposite ends of the mold, slots in said arbors, means engaging 15 said slots for drawing said side plates toward each other to clamp and hold the said parts of the mold together, substantially as described.

THEODORE CORNUELLE.
